UNITED STATES PATENT OFFICE.

CHARLES A. RENHOLDT, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

PULL-SWITCH.

1,400,376.

Specification of Letters Patent. Patented Dec. 13, 1921.

Application filed April 7, 1917. Serial No. 160,475.

To all whom it may concern:

Be it known that I, CHARLES A. RENHOLDT, a citizen of the United States of America, and residing at Bridgeport, in the county of 5 Fairfield and State of Connecticut, have invented a certain new and useful Improvement in Pull-Switches, of which the following is a specification.

My invention relates to electric pull 10 switches and the object of my invention is to provide an improved switch mechanism of simple construction embodying certain features of novelty hereinafter described or 15 illustratively embodied in one form in the accompanying drawings in which—

Figure 1 is a broken elevation of a pendant switch;

Fig. 2 is a side elevation of the switch body at right angles to Fig. 1;

Fig. 3 is a side elevation of the switch body from the side opposite that shown in 20 Fig. 1;

Figs. 4 and 5 are cross sections on the lines 4—4 and 5—5, Fig. 2, respectively;

Fig. 6 is an elevation of one portion of the 25 insulating body with the metal parts removed;

Fig. 7 is a detached perspective of the operating mechanism of the switch; and

Fig. 8 is an elevation of the other insulating body piece of the switch, with the switch terminals in place.

In the form here shown the mechanism to which my invention relates is embodied in a 30 switch of the pendant type comprising a metallic casing having interlatching cap 10 and shell 11 lined with insulating 12 and having at one end a bushing 13 through which the lead wires are introduced to the 35 switch and at the other end a bell 14 through which the pull chain 15 is guided. Within the casing is contained the insulating switch body comprising buttons 16 and 17 of porcelain or other insulating material 40 rounded on their outer faces to conform to the contour of the metallic casing, but flat on their opposed faces which are spaced apart by the standards 18, 19 and 20 to afford space for the switch mechanism. The standard 18 45 is secured at one end by a screw 21 passing through a wire terminal plate 22 let into a recess 23 on the outer face of button 17. Beneath the offset end of the standard 18 is 50 clamped the switch terminal 24. The stand-

ard 19 is secured at one end by the screw 25 55 which passes through the wire terminal plate 26 on button 16. The opposite end of this standard is secured to button 17 by screw 27 which passes through the strap 28 let into a recess in the outer face of button 17 and connected by a rivet 29 to the base of the other switch terminal 30 so that a connection from wire terminal 26 is established through standard 19 and strap 28 to switch terminal 30. 60

The two switch terminals 24 and 30 are arranged on diametrically opposite sides of a generally circular boss formed on the inner face of the button 17 and comprising four 65 symmetrically-arranged, ratchet-like teeth 31 spaced apart by depressions 32. The terminals 24 and 30 lie in opposite depressions 32 and are provided with upstanding inclined flanges 33 which rise to the height of the adjacent ratchet-like tooth 31. The incline of the flanges 33 is substantially followed in the inclination 34 rising from the depressions 32 to the top of the ratchet teeth 31 lying between the switch terminals. 70

The switch bar 35 comprises a bridge piece 80 spanning the switch terminals 24 and 30 in “on” position and lying in the interposed recesses 32 in its “off” position. It is mounted freely on switch spindle 36 and is actuated by the switch spring 37 to make and 85 break contact with a snap action. One end of the spring 37 engages the switch bar 35, and the opposite end a crown piece 38 fast on spindle 36 and having arms 39 which afford points of engagement for the ratchet 90 teeth 40 carried by the oscillatory operating plate 41 of insulating material on which is supported the chain rail 42. The plate 41 is journaled on the switch spindle 36 and is subjected to the action of the return spring 95 43, the opposite end of which is engaged by an abutment thimble 44 having a rectangular head 45 seated in correspondingly shaped recess 46 in the inner face of the button 16 and having a cross slot 47 for the 100 reception of a screw driver or the like entering through the passage 48 so that the thimble may be displaced longitudinally on the spindle 36, the tension of the spring 43 adjusted and the head reseated in its recess 105 46 to maintain the tension at the degree desired.

The snap action of the switch is secured

by the detaining engagement of the sharply inclined faces 34 of the ratchets 31 at one stage, and the correspondingly inclined flanges 33 of the switch terminals, at the 5 succeeding stage of rotation. These inclines are preferably so sharp that the tension of the operating spring 37 is insufficient of itself to force the arms of the switch bar up the inclines. The rise of the switch bar out 10 of the recesses 32 is accomplished by means of a cam piece 49 mounted on the spindle 36 and moving with the latter. This cam is shown as a cupped annulus having up-standing cam wings 50 which engage oppositely cammed wings 51 on the switch bar 35. The pairs of cams 50 and 51 on the cup 49 and switch bar 35 respectively are of such pitch that upon a quarter-turn of the spindle 36 the switch bar is lifted by the 15 cams 50 out of the depressions 32. It is thereby freed from the detaining engagement of the inclines 34 and moves to succeeding position under the influence of the tensioned spring 37. As the switch bar 20 moves to its next position its arms run down the inclined faces of the ratchet teeth 31 and fall into the succeeding pair of recesses 32 where they are halted not only by their engagement with the sharp inclines 33 or 25 34, but also by the engagement of the cam flanges 51 with the shoulders 52 formed by the cutting away of the side of the cup 49 to form the cams 50 thereof.

The method of mounting the cam piece 49 upon the spindle 36 is immaterial, a simple method being illustrated by forming a flat 53 on the side of the spindle 36 which takes into a corresponding aperture in the base of the cup 49. The spindle is retained on button 17 by passing through hole 54 in the latter into a recess 55 formed in the outer face thereof, where it is engaged by a split washer 56. A bearing washer 57 for the cam piece 49 may be seated in a recess 58 at the base 45 of the well 59 in which the cam 49 rotates.

The operation of the switch is readily understood. In normal condition, the parts take the position indicated, with the operating plate 41 halted against the spacing standard 19. When the pull chain 15 is actuated, the spindle 36 is rotated with the crown piece 38, thus placing the switch spring 37 under tension since the switch bar 35 is temporarily detained by its engagement with the inclines 33 or 34. On this rotation of the spindle 36, however, the cam piece 49, fast thereon, is simultaneously rotated thus causing the switch bar 35 to rise until it is free of the detaining inclines 33 or 34, whereupon it is snapped by the spring 37 to its succeeding position. As the switch bar rotates, it is depressed by spring 37 so that it runs down the inclines of the ratchet teeth 31 and falls into the interposed channels 32, where it is halted until the succeed-

ing actuation of the chain again causes a repetition of the operations just described and the consequent advance of the contact bar to its next operation.

Various modifications in details of construction and arrangements of parts will readily occur to those skilled in the art without departing from what I claim as my invention. 70

I claim:—

1. In an electric switch, a rotary switch bar, an insulating base having bosses forming detents, switch contacts arranged on said base and shaped to form detents spaced from said bosses, cams on said switch bar, and a rotary lifting cam member co-operating with said cams on the switch bar to lift the same over said detents. 80

2. In an electric switch, a rotary switch bar, an insulating base having bosses forming detents, switch contacts arranged on said base and shaped to form detents spaced from said bosses, cams on said switch bar, and a rotary lifting cam member coöperating with said cams on the switch bar to lift the same over said detents, together with a torsion spring engaging said switch box to impart a positive forward throw thereto after it is freed from said detents by the co-operating cams. 85 90 95

3. In an electric switch, a rotary switch bar, an insulating base having bosses forming detents engaged by said switch bar, a rotary spindle on which said switch bar is freely journaled and a cam arranged on said spindle between said base and switch bar, and a coöperating cam on the switch bar for displacing the latter longitudinally on the spindle to free it from said detents. 100

on the spindle to free it from said detents. 4. In an electric switch, a rotary switch 105 bar having offset cam shaped wings, a base having bosses constituting detent means engaged by the outer ends of the switch bar and means engaging said cam wings to shift the switch bar out of engagement with said 110 detent means.

5. In an electric switch, a switch spindle, a cam fast thereon comprising a cup-shaped body having its sides cut away to form cam wings, in combination with a rotary switch bar journaled on said spindle and detent means engaging said switch bar and from which the latter is freed by the action of said cam. 115

6. In an electric switch, a rotary switch 120
bar having offset cam shaped wings, a spindle
on which said bar is freely journaled, detent
means engaging said switch bar and cam
means on the spindle engaging said cam
wings on the switch bar to free the latter 125
from the detent means.

7. In an electric switch, a rotary switch bar having offset cam shaped wings, a spindle on which said bar is freely journaled, detent means engaging said switch bar and 130

cam means on the spindle engaging said cam wings in the switch bar to free the latter from the detent means, said cam means on the spindle comprising a cup-shaped member having its side walls cut away to afford cam wings engaging the cam wings on the switch bar.

8. In an electric switch, a rotary switch bar having cam wings, an insulating base 10 having a toothed boss on which said switch bar rests and by the teeth of which it is detained, and rotary cam means engaging the cam wings of the switch bar for positively shifting the switch bar away from 15 the base and out of engagement with the detaining faces of said teeth.

9. In an electric switch, a rotary switch bar having cam wings, switch terminals bridged thereby, said terminals having a 20 contact area and on one side thereof detent flanges engaged by the switch bar, together with rotary cam means engaging the cam wings of the switch bar for positively shifting said bar away from the base and out of 25 detaining engagement with said flanges.

10. In an electric switch, an insulating base recessed to form a well and having a toothed boss surrounding said well, a rotary switch bar resting upon said boss and 30 detained by the teeth thereof, said switch bar having cam wings entering said well in the base, in combination with cam means arranged in said well and coöperating with said cam wings for shifting the switch bar 35 out of detaining engagement with said teeth, for the purpose described.

11. In an electric switch, an insulating base having a toothed boss with depressed areas between adjacent teeth, and a rotary 40 switch piece engaging said boss and detained in a position of rest in said depressed areas, cam wings on said switch bar, together with cam means engaging the cam wings on the switch bar for lifting said switch bar out 45 of said depressed areas to free it from detaining engagement therein.

12. In an electric switch, a pair of insulating buttons spaced apart to accommodate the switch mechanism, a pair of bosses on 50 the inner face of one of said buttons, a pair of switch terminals alternating with said bosses, a pair of wire terminals mounted one on the outer face of each of said buttons, and means for electrically connecting said 55 wire terminals with the respective switch terminals, a rotary switch piece alternately engaging and detained by said bosses and switch terminals, a switch spindle upon which said switch bar is freely journaled, a 60 switch spring tensioned by the rotation of said spindle during the detention of said switch bar by said detents, and cam means on said spindle for shifting said switch bar longitudinally of the spindle out of 65 detaining engagement with said detents to

permit the rotation of said bar by said spindle.

13. An electric switch comprising a rotary switch bar, an insulating base having alternate bosses and switch terminals thereon shaped to form detents engaged by said switch bar, a rotary spindle on which said switch bar is freely journaled, cam wings on the switch bar, and a coöperating cam on said spindle for displacing said switch bar 70 longitudinally on the spindle to free it from said detents. 75

14. An electric switch comprising a rotary switch bar, an insulating base having alternate bosses and switch terminals thereon shaped to form detents engaged by said switch bar, a rotary spindle on which said switch bar is freely journaled, and a cam on said spindle for displacing said switch bar 80 longitudinally on the spindle to free it from said detents, together with a cam on said switch bar coöperating with the cam on the spindle. 85

15. An electric switch comprising a rotary switch bar having arcuate cam flanges, 90 an insulating base having alternate bosses and switch terminals thereon shaped to form detents engaged by the body of the switch bar, a rotary spindle on which said switch bar is freely journaled and a cam on 95 said spindle having cam wings coöperating with the cams on the switch bar for displacing the latter longitudinally on the spindle to free it from said detents.

16. In an electric switch, a switch bar 100 having offset arcuate cam lugs, detents engaging the body of said switch bar, a spindle on which said switch bar is freely journaled and a hub fast with said spindle and having arcuate cam teeth engaging the cam lugs on the switch bar and serving on the rotation of the spindle to shift the switch bar longitudinally of the spindle out of engagement with its detents, said hub having stop faces engaged by said cam lugs 105 on the switch bar to halt the latter after partial rotation, substantially as described. 110

17. In an electric switch, a rotary switch bar, a course having alternate conductive and non-conductive detaining rises over 115 which the switch bar rides, and ratchet-operated mechanism for rotating the switch bar, said mechanism including cam means for lifting the switch bar over the rises of its course. 120

18. In an electric switch, a rotary switch bar, a course having alternate conductive and non-conductive detaining rises over which the switch bar rides, and ratchet-operated mechanism for rotating the switch bar, said mechanism including cam means for lifting the switch bar over the rises of its course, and torsion spring means for rapidly advancing the bar on its course after it has reached the rise crest. 125 130

19. In an electric switch, a rotary switch bar, a course having alternate conductive and non-conductive detaining rises over which the switch bar rides, and ratchet-operated mechanism for rotating the switch bar, said mechanism including cam means for lifting the switch bar over the rises of its course, and spring means acting both in compression and in torsion to both rapidly advance the bar on its course after it has reached the rise crests, and to force it downward on its course into engagement with the successive detaining rises.
20. In a switch, a rotary switch bar having cam wings, a hill and valley course traveled thereby, alternate conductors and non-conductors at succeeding rises, cam means engaging the cam wings of the switch bar element to lift it with lagging action over the rise and a torsion spring engaging said switch bar and serving on the escape of the bar from the rise to impart a rapid forward impulse to the bar.

In testimony whereof I have signed my name to this specification.

CHARLES A. RENHOLDT.
